UNITED STATES PATENT OFFICE.

WILLIAM G. REYNOLDS, OF CHICAGO, ILLINOIS.

PRINTING FORM AND TYPE.

No. 927,873.

Specification of Letters Patent. Patented July 13, 1909.

Application filed February 5, 1909. Serial No. 476,248.

To all whom it may concern:

Be it known that I, WILLIAM G. REYNOLDS, citizen of the United States, residing at Chicago, in the county of Cook and State of Illinois, have invented certain new and useful Improvements in Printing Forms and Type, of which the following is a specification.

This invention relates to printing forms 10 and type, and includes a special form of type, bars upon which the type is strung and held, and a chase or frame for holding the bars.

The invention is particularly useful in 15 connection with address printers, but nevertheless may be applied to any purpose for which it is adapted. The type will be composed on the bars, and then the bars will be inserted in a chase, making a form for printing, as hereinafter described.

In the accompanying drawings, Figure 1 is a plan view of the form; Fig. 2 is a side elevation of one of the type bars with the type thereon; Fig. 3 is a top view of Fig. 2; Fig. 4 is an end view of Fig. 2; Figs. 5, 6, 7 and 8 are side views of the ends of different type bars; Fig. 9 is a plan view of the end of the bar shown in Fig. 8.

Referring specifically to the drawings, 10 Fig. 1 indicates one form of type bar, comprising a rod or bar shown as of greater width than thickness, and rounded or otherwise shaped at its edges to conform to the shape of the type used, and this bar is reduced at its ends 35 as indicated at 10^a, so that said ends will fit under the flanges of the chase or holder to be hereinafter described. Various other forms of bars are shown in Figs. 6 to 9 inclusive, one having dropped ends as in Fig. 6, another having single beveled ends as indicated in Fig. 7, and another having tapered ends as shown in Figs. 8 and 9, the object being to provide a construction whereby the type may be readily slipped or strung on 40 the bars, and also with the object of elevating the face of the type slightly above the flanges of the chase in which it is held.

The type are indicated at 11 and as shown are C-shaped, being formed of pieces or 50 strips of metal, such as sheet metal, bent to such shape, and embossed or stamped to produce type faces on the outer side thereof. The shape may be varied as desired, retaining, however, the idea of a type which 55 can be strung on a bar or rod when composed, and retained thereon during the print-

ing operation, the curved or C-form being a preferred form shown for the purpose of illustration, and capable of being produced in a stamping or embossing press, without 60 casting, although the type may be cast if desired.

The chase consists of a plate 12 having its opposite edges bent up and over as indicated at 13 to engage over the ends of the type bars 65 when the same are placed therein. Said edges form overhanging flanges and grooves at the sides of the plate. The width of the chase agrees with the length of the type bars, which are slid in with their ends under the 70 overhanging flanges and are thereby retained in position, producing a form which is capable of use in a bed and cylinder press or otherwise. The chase is formed of comparatively thin metal, so that the type faces 75 will project above the flanges of the chase in position to print upon paper placed upon the form.

The type is composed by stringing the 80 type on the bars, by means of a type setting machine or otherwise, and the bars are placed in the chase as described. Blank bars may be used for spacing.

By the use of this invention, particularly 85 in connection with a type setting machine, much of the labor incident to composition and type setting is avoided, and without great danger of the type being pied, and the type may be readily distributed by slipping 90 the same off the bars and then distributing 95 the type to the case, or to the magazine of the type setting machine.

The invention is not limited to the exact form shown, as various changes may be made in some or all of the parts thereof within the scope of the appended claim.

I claim:

A form comprising a chase consisting of a sheet metal back plate having overhanging flanges at the edges thereof, bars in the 100 chase with their ends engaged under said flanges, and type mounted on said bars and consisting of substantially C-shaped strips the ends of which extend around opposite edges of the bars and are confined between 105 the back of said bars and the back plate.

In testimony whereof, I affix my signature in presence of two witnesses.

WILLIAM G. REYNOLDS.
